United States Patent Office

Des. 226,637
Patented Apr. 3, 1973

226,637

FABRIC POCKETBOOK

Margo Jeanette Rauch, 1657 E. 19th St.,
Brooklyn, N.Y. 11229

Filed May 10, 1971, Ser. No. 142,107

Term of patent 14 years

Int. Cl. D3—02

U.S. Cl. D87—3 F

FIG. 1.

FIG. 2.

FIG. 1 is a front perspective view of the fabric pocketbook, embodying the features of my new design, and FIG. 2 is a rear perspective view thereof.

I claim:

The ornamental design for a fabric pocketbook, substantially as shown and described.
